UNITED STATES PATENT OFFICE

2,594,360

GARAGE DOOR

Siegmund Siperek, Detroit, Mich.

Application June 20, 1950, Serial No. 169,080

2 Claims. (Cl. 20—16)

1

This invention relates to doors of garages and similar structures, and, more particularly, to garage doors which are pivoted for upward and downward swinging as a single flat unit to open overhead and lower closed portions. Such doors are usually counterbalanced, as by springs or weights, to assist their easy and smooth operation; but neither the counterbalancing nor the particular pivot structure or mechanism are features of the present invention which lies in the manner in which the door proper is cooperatively fitted in the door frame to produce the desirable features about to be explained.

An object of the invention is to provide in a door of this type a geometric configuration of the two upright edges of the door panel and of the corresponding door framework, whereby a firm and draft-proof seal therebetween may be assured when the door is in its lower closed position, and a practically immediate separation of these edges of the door from the said frame members is insured upon the initial opening action or raising of the door.

An important object of the said invention is to dispense, in such a door, with the usual overlapping frontal or rear jamb strips or cleats such as are commonly associated with such doors as stops or weather-sealing means; and further, to provide an arrangement whereby the door may be hung flush with the front face of its frame to make available a maximum of floor space within the garage or building without detracting from the efficiency of the door as a closure.

More particularly, the said invention contemplates, in a pivoted upwardly swingable door of this type, the converging downwardly of the two lateral edges of the door and the converging in counterpart thereof of the opposed edges of the two vertical door frame members whereby, in the lower position of the said door, the edges, thereof of about the opposed inclined edges of the door frame with a wedging action but are readily separated therefrom upon the initial pivotal raising of the door as a reverse function of such wedging action; the resulting progressive separation of the opposed edges of the door and its frame members providing increasing clearance for the free swinging of the door about its pivotal axis during the raising operation.

The elimination of vertical stops, cleats or jamb strips is sought in order to simplify construction, to modify the usual method of sealing the door upon closure, and to permit the advancing of the closed door position to a maximum extent within the door frame for the purposes referred to.

2

In carrying the said invention into effect, I may adopt the novel construction and arrangement of parts hereinafter described, by way of example, having reference to the accompanying drawing, wherein:

Figure 1 is a front elevation of the pivoted upwardly swingable door, the said door being shown in its lower or closed position;

Figure 2 is a similar elevation showing the door in a partially raised position;

Figure 3 is a horizontal sectional view taken on a plane indicated by the line 3—3 in Figure 1;

Figure 4 is a vertical sectional view through the door taken on a plane indicated by the line 4—4 in Figure 1; and

Figure 5 is a similar view to Figure 4 showing the door partly raised.

Similar characters of reference indicate similar parts in the several figures of the drawing.

10 indicates a garage or similar building wall having a door opening therein, 11' indicating the lintel defining the top of the said door opening and 11 and 12 the side frame members of the said door opening, which frame members are usually in the form of posts having parallel vertical edges presented toward one another. However, in the present case, these frame members are characterized by their opposed edges (which in the illustrated example are provided with facings 13 and 14) being inclined from the vertical so that they are downwardly converged relatively as will be quite clear from an examination of Figures 1 and 2 of the drawing.

Hereinafter, for the sake of simple description, reference to the opposed edges of the frame members 11 and 12 will be intended as referring to the facings 13 and 14 where these are provided.

The door itself 15 is of a configuration complementary to the resulting opening, in that it is wider at the top than at the bottom, its lateral edges 16 and 17 converging downwardly of the door to agree with the converging of the opposed edges of the said frame members 11 and 12. Thus, 45 when the door is in its lower closed position, its edges impinge the posts or frame members with a wedging action insuring a tight closure of a nature rendering unnecessary the use of vertical stops, cleats or jamb strips overlying the joint between the edges of the door and the abutting side frame members.

The door 15 is of the upwardly swingable pivoted type, as stated, and is shown as being provided with rearwardly extending brackets 18 pivoted at 19 to the garage or building structure, but, as the mechanical arrangement of this

pivotal support is not in the nature of an invention, it need not be described in further detail herein. Any suitable counterbalancing means (not shown) for the door may be provided as is usual in this type of upwardly swinging door.

It should be noted that the door does not drop vertically into position in the wedge-shaped door opening but is actually performing a swinging motion about the pivots 19, whereby a particularly desirable closing action between the impinging inclined surfaces takes place as there is a combination of both vertical and lateral motions of the edges of the door against and the opposed edges of the door posts or frame members as the closing operation is effected. The reverse action takes place, of course, as the door is opened, and the result is a desirable degree of tightness in the door when closed without any undesirable interference with the free and unrestricted opening action of the door.

With a door constructed to embody this invention, the upper portion of the door may or may not completely close against the lintel 11; although in the example the said lintel is shown as being provided with a bumper strip 20.

It should also be noted, as important, that although the door is of a swinging type it abuts the lateral frame members with a downward pressure permitting a tightness and fitting not previously possible in swinging doors as heretofore built.

Where facings such as 13 and 14 are provided, these may be of wear-resisting material such as of metal, or of resilient material such as of leather, to provide impinging surfaces of desirable physical characteristics to meet the desires of the builder.

While the frame members or posts are described as being free from jamb strips or cleats, such as are usually associated with swinging doors, it does not contemplate that mere abbreviated forms thereof, such as stops at the top front or bottom rear of the door may not be used although I do not regard such stops as at all necessary.

The degree of taper shown in the drawings is exaggerated for clear illustration, as applied to most large doors, and in actual practice I have found that, as an example, a door seven feet high which is nine feet three inches wide at the top and nine feet wide at the bottom works very satisfactorily.

This invention may be developed within the scope of the following claims without departing

from the essential features of the said invention, and it is desired that the specification and drawing be read as being merely illustrative of a practical embodiment of the same and not in strictly limiting sense.

What I claim is:

1. In a building structure, in combination, a pair of posts defining the sides of a doorway and extending upwardly from a floor or sill, said posts having their opposed edges inclined and converging toward the bottom of said doorway, a door normally vertically disposed in its closed position between said opposed edges of said posts, the lateral edges of said door converging downwardly to conform to the downwardly tapering doorway, and hinge supports for said door pivoted materially to the rear of said door whereby said door may be swung upwardly and rearwardly to an open overhead position, and downwardly into simultaneous wedging impingement with said posts and with the floor or sill below said doorway.

2. In a building structure, in combination, a pair of upright posts defining the sides of a doorway, said posts having their opposed edges inclined and converging toward the bottom of said doorway, said posts being free from jamb strips such as usually project inwardly of a door opening, a door normally vertically disposed in its closed position between said opposed edges of said posts, the lateral edges of said door converging downwardly to conform to the downwardly tapering doorway, and hinge supports for said door pivoted materially to the rear of said door whereby said door may be swung upwardly and rearwardly to an open overhead position, and downwardly into wedging impingement with said posts.

SIEGMUND SIPEREK.
